STEAM PRESSER FOR FABRICS OR A LIKE ARTICLE

Leonard Osrow, Glen Cove, N.Y., assignor to Osrow
Products Company, Inc., Glen Cove, N.Y., a corporation of New York

Filed Nov. 4, 1969, Ser. No. 19,936

Term of patent 14 years

Int. Cl. D15—07; D23—04

U.S. Cl. D49—13

FIG. 1

FIG. 2

FIG. 3

FIG. 4

FIG. 5

FIG. 6

FIG. 1. is a top perspective view of a steam presser for fabrics or a like article showing my new design;

FIG. 2 is a right side view thereof;

FIG. 3 is a front view thereof;

FIG. 4 is a top view thereof on a greatly enlarged scale;

FIG. 5 is a back view thereof on an enlarged scale; and

FIG. 6 is a sectional view taken along the line 6-6 of FIG. 2.

The left side is the same as the right side.

The bottom of the steamer is plain.

I claim:

The ornamental design for a steam presser for fabrics or a like article, substantially as shown and described.
